UNITED STATES PATENT OFFICE.

PAUL H. SMITH, OF COLUMBUS, OHIO.

LEVER FOR OPERATING TRUNK-TRAYS.

SPECIFICATION forming part of Letters Patent No. 609,563, dated August 23, 1898.

Application filed November 27, 1897. Serial No. 659,950. (No model.)

To all whom it may concern:

Be it known that I, PAUL H. SMITH, a citizen of the United States, residing at Columbus, in the county of Franklin and State of Ohio, 5 have invented certain new and useful Improvements in Levers for Operating Trunk-Trays; and I do hereby declare the following to be a full, clear, and exact description of the invention, such as will enable others skilled in the art to which it appertains to make and use the same.

The object of my present invention is to provide an improved construction of lever for operating a tray or trays in such a trunk as 15 is shown in my application for Letters Patent of the United States filed April 2, 1897, Serial No 630,400.

In the annexed drawings, Figure 1 is a perspective view of an end of a trunk, showing 20 a lever chamber or compartment, the lever being indicated by dotted lines. Fig. 2 is a transverse sectional view taken on a plane indicated by the line $x-x$, Fig. 1, showing in elevation the inner side of the end of the 25 trunk with the tray-operating lever in position; and Fig. 3 is a perspective view of the upper end of the fulcrumed part of the lever.

Like characters of reference in the several views indicate corresponding parts.

1 designates the lower or pivoted part of 30 the lever, which is preferably pivoted or fulcrumed near the bottom of the trunk upon a pin 1^a , extending between the end wall of the trunk and the transverse partition that forms, 35 in connection with said end wall, the lever-compartment. The upper end of this pivoted part of the lever has a socket portion 2, that is open in the upper part of its rear side, as indicated at 2^a , and closed or solid at its front 40 side, as indicated at 2^b , while the side walls of the said socket portion are made with Γ -shaped slots 2^c , open at their lower ends. The extensible part 3 of the lever consists simply of a flat bar of the same cross-section as the 45 opening of the socket portion, so as to be freely movable in said socket longitudinally with respect to the pivoted part 1 of the lever, and the said extensible part has at its upper end a handle 3^a and in its lower end a pin 3^b , that 50 projects laterally from both sides of the ex-

tensible part, so that when the lever is pulled out the pins will extend into the Γ -shaped slots.

To reciprocate the extensible portion of the lever, it is pulled up in the socket as far as desired to secure powerful leverage, but not so far that the pin 3^b shall stand in or opposite the small divergent portion of the slot at the upper part of the socket, after which the lever may be easily drawn toward the front of 60 the trunk. When the lever-handle is thus drawn toward the front of the trunk, it will stand outward and possibly in the way of the user, and with the construction shown the extensible part of the lever may be further 65 lifted in the socket until the pin 3^b shall stand opposite the small divergent part of the slots, when it may be placed rearwardly to lie in the position indicated by broken lines, Fig. 2.

The cord 4, which runs from the tray or 70 tray-supporting devices, may be attached to the lever by means of a tension device, substantially as explained in my aforesaid application for patent.

What I claim, and desire to secure by Letters Patent, is—

1. In a trunk of the kind described, a tray-elevating lever comprising a pivoted part, and a handled part sliding longitudinally with respect to and parallel to said pivoted part, and 80 means, substantially as described, permitting said sliding part to be turned backward on said pivoted part only when the sliding part is drawn out, as set forth.

2. In a trunk of the kind described, a tray-elevating lever comprising a pivoted part having at its upper end a socket 2, open at its back, and its sides provided with slots or channels, and an extensible part in said socket having a pin to enter said slots or channels 90 to permit the bending of said extensible part with respect to the pivoted part, substantially as shown and described.

3. In a trunk, the combination with an end wall thereof, of a lever, comprising a pivoted part and a handled part sliding longitudinally upon and parallel to said pivoted part, said sliding part being adapted when drawn out to be bent backward from said pivoted part, two vertically-arranged pulleys on said end 100

wall near the rear corner of the trunk, a horizontally-arranged pulley at the bottom of the trunk, a cord attached to said lever and passing over said pulleys, and a partition to in-
5 close said lever and pulleys and separate the same from the main receptacle of the trunk, substantially as described.

In witness whereof I have hereunto subscribed my name this 23d day of November, 1897.

PAUL H. SMITH.
